(57) **CLAIM**

The ornamental design for a baby walker jet toy, as shown and described.

DESCRIPTION

FIG. 1 is a perspective view from above and to the front of my new design for a baby walker jet toy.

FIG. 2 is a side elevational view of the toy of my new design.

The opposite side would be a mirror image of FIG. 2.

FIG. 3 is a front end elevational view thereof.

FIG. 4 is a rear end elevational view thereof.

FIG. 5. is a top plan view thereof; and,

FIG. 6 is a bottom plan view thereof.

1 Claim, 5 Drawing Sheets
